UNITED STATES PATENT OFFICE.

LÉON BENOIT, OF VANCOUVER, BRITISH COLUMBIA, CANADA.

WRENCH.

1,355,883.

Specification of Letters Patent. Patented Oct. 19, 1920.

Application filed February 15, 1919. Serial No. 277,331.

To all whom it may concern:

Be it known that I, LÉON BENOIT, a subject of the King of Great Britain, and a resident of the city of Vancouver, in the Province of British Columbia, Canada, have invented certain new and useful Improvements in Wrenches, of which the following is a specification.

My invention relates to improvements in wrenches, and the object of my invention is to devise a wrench provided with a sliding jaw capable of automatic locking when applied to a nut to turn the same, or other analogous purposes, and which is characterized by the simplicity of its parts and its direct action while possessing great strength besides being cheap to manufacture.

I attain this object by the construction illustrated in the accompanying drawing 20 in which—

Figure 1 is an outside elevation of the wrench.

Fig. 2 is an elevation, in part section.

Fig. 3 is a cross section taken on the line 25 5—5 of Fig. 2.

Similar figures of reference indicate similar parts throughout the several views.

It may be here stated that the construction of the automatic locking jaw hereinabove described may be applied to all wrenches having sliding jaws, and particularly to those pressure-operated, but for the purpose of illustration a wrench having a simple straight shank 1 and rigid upper 35 jaw 2 is shown.

Mounted on the shank 1 for vertical sliding movement thereon is the sliding jaw, indicated generally by the numeral 3 and consisting of a plate 4 doubled over to embrace the rear edge of the shank to form side plates 5 and 6 which side plates provide a support for the rocking jaw member 7, which is hung between the plates on a pivot 8, this pivot extending through a slotted hole 9 in the jaw into both plates 5 and 6, from which it will be seen that the jaw, while being capable of a swinging movement, is also capable of lateral movement at its upper end. Adjacent the pivot 50 hole 9 the rear edge of the jaw is preferably rounded, or otherwise suitably shaped as at 10, the rounded portion normally engaging a correspondingly shaped seat 11 formed on the plate 4, as shown in Fig. 2, while on its 55 opposite edge the jaw is flattened, as at 12, so that it may seat firmly, when moved later-

ally outward, on the closure 13 extending between the plates 5 and 6, which closure may be formed by turning one of the plates at right angles to bridge the space between the plates. The jaw 7 is mounted so that its upper edge is normally inclined upwardly from its point of pivotal connection so that it is compressible when the wrench is placed on a nut, the closure 13 being cut away, as at 14, to allow for such depression, and the jaw is maintained in normal position by means of a spring 15 one end of which is inserted in a slot 16 in the jaw body while its opposite end engages a pin 17 secured into the plates 5 and 6. The rear edge of the jaw 7 is provided with teeth 18 adapted to engage teeth 19 formed on the front edge of the shank 1 when the jaw is locked, as hereinafter described, and on both sides 75 the shank is reinforced by strips 20 and 21, which may be formed integrally with the shank or built on thereto and which serve not only to stiffen it but also to form guides for the plate 4 which is crimped in, as at 22 in Fig. 3, to conform to the cross sectional shank formation.

As it is sometimes desirable to maintain the jaw 7 in its locked position, a lock is provided consisting of a pawl 23 fulcrumed on a pin 24, the inner end of which pawl is normally clear of the jaw 7 but which when the jaw is locked, that is, when the jaw teeth 18 are in engagement with the shank teeth 19, may be swung upwardly to engage the front edge of the jaw, which is formed straight, as at 25, to receive the inner end of the pawl. In the locking position the outer end of the pawl projects below the plates 4 and 5 so that when it is desired to unlock the jaw the inner end may be depressed and removed clear of the same by upward pressure on the said outer end, and in order to maintain the pawl in either its locking or unlocked positions it is provided with a spring member 26 having a ball shaped projection 27 adapted to engage, as the case may be, cup-shaped depressions 28 and 29 formed in the closure 13, as shown in Fig. 2, the projection 27 engaging depression 28 when the pawl is unlocked and depression 29 when it is in the position locking the jaw 7 to the shank.

The manner in which the device operates 110 will be readily apparent, on reference being had to Fig. 2, particularly as it will be seen

that on placing the wrench on a nut, the inclined upper edge of the jaw 7 will be depressed, causing the jaw to swing on the pivot 8 and carry its teeth 18 into engagement with the shank teeth 19, thus locking the sliding jaw 3 against retraction, and if it is desired to lock the jaw 7 against disengagement, the pawl 23 is swung into position, as already described. The strain of turning the nut tends to create both an outward and an inward lateral movement of the jaw 7 at its upper end according to the respective direction of rotation of the wrench, the pressure of which movements, on account of the slotting of the hole 9 is taken up respectively by the closure 13 and the seat 11 so that all strain is taken off the pivot 8 entirely, thus utilizing fully the whole strength of the plate of which the jaw member 7 is formed.

From the foregoing it will be seen that I have devised a simply constructed, inexpensive and strong direct-acting automatic locking wrench.

25 What I claim as my invention is:

1. A wrench comprising a toothed shank having a rigid jaw, a yoke member slidable thereon provided with a pivot, a jaw member consisting of a plate having a slotted hole through which said pivot extends whereby said plate is supported for swinging or inward or outward lateral movement, the upper edge of said plate extending above the yoke and being inclined outwardly and upwardly and its rear edge being provided with teeth adapted to coöperate with the shank teeth when swung inwardly to lock the jaw against retraction,

and means excluding the pivot for taking up the inward lateral strain on the jaw 40 when the same is under turning pressure.

2. A wrench comprising a toothed shank having a rigid jaw, a yoke member slidable thereon provided with a pivot, a jaw member consisting of a plate having a slotted hole through which said pivot extends whereby said plate is supported for swinging or inward or outward lateral movement, the upper edge of said plate extending above the yoke and being inclined outwardly and upwardly and its rear edge being provided with teeth adapted to coöperate with the shank teeth when swung inwardly to lock the jaw against retraction, and means excluding the pivot for taking up the outward lateral strain on the jaw 50 when the same is under turning pressure.

3. A wrench comprising a toothed shank having a rigid jaw, a pivot carrying yoke member slidable on said shank, a jaw member supported on said pivot for swinging in inward and outward lateral movement, the upper edge of said jaw member extending above the yoke, and the rear edge thereof being provided with teeth adapted to interlock with the shank teeth when swung inwardly to secure the jaw against retraction, means carried by the yoke for locking said jaw against accidental disengagement from the shank, and means for retaining said 60 last-mentioned means either in an operative or an inoperative position.

Dated at Vancouver, B. C. this 16th day of January, 1919.

LEON BENOIT.
